CLAIM

We claim the ornamental design for the two-well diagnostic test kit with specimen-handling tool, as shown and described.

DESCRIPTION

FIG. 1 is an end view of the diagnostic test kit of the present invention.

FIG. 2 is a top plan view of the diagnostic test kit of the present invention.

FIG. 3 is a side elevational view of an elongated side of the diagnostic test kit of the present invention, where both elongated sides are identical.

FIG. 4 is another end view of the diagnostic test kit of the present invention.

FIG. 5 is a perspective view of the diagnostic test kit of the present invention; and,

FIG. 6 is another perspective view of the diagnostic test kit of the present invention.
